(57) **CLAIM**

The ornamental design for a fitted sheet with corner straps, as shown and described.

DESCRIPTION

FIG. 1 is a perspective view of a fitted sheet with corner straps showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of a portion indicated with numeric 9 in FIG. 1.

The dash dot dash broken lines encircling claimed subject matter shown in FIGS. 2 and 9 depict the cut lines of the enlarged views and form no part of the claim. All other broken lines depict portions of the fitted sheet with corner straps that form no part of the claimed design.

1 Claim, 9 Drawing Sheets
